UNITED STATES PATENT OFFICE.

WILLIAM TAYLOR, OF ALLEGHENY, PENNSYLVANIA.

NAIL.

SPECIFICATION forming part of Letters Patent No. 405,972, dated June 25, 1889.

Application filed April 9, 1888. Serial No. 270,152. (No model.)

To all whom it may concern:

Be it known that I, WILLIAM TAYLOR, a citizen of the United States, residing at Allegheny, in the county of Allegheny and State of Pennsylvania, have made a new and useful Improvement in Nails or Spikes, which will be readily understood from the following description, taken in connection with the accompanying drawings.

10 The invention relates to an improved wire nail—that is to say, a nail made from continuous wire round in cross-section—and it has several important objects in view. I aim to provide a nail which shall contain as little 15 as possible of the wire metal, and which shall yet be as strong and as tenacious as are those wire nails which preserve the entire body of the said wire.

20 In producing the nails I commence with a wire of the proper gage, round in section, and subject it to a series of steps of drawing, for the purpose of removing the metal on two of the sides; but I allow the intermediate metal to remain of the same diameter as was the 25 initial round wire. This changing of the form of the wire is effected by means of draw-plates so constructed and arranged that the wire is gradually made thinner; but it is done in such way that the surface texture, generally called the "skin," is not impaired. 30 The blanks from which the nails are ultimately formed may be regarded as flattened relatively to the initial round wire, and yet they are not made flat by crowding any of the metal outward from the axis of the wire, but 35 by drawing away the surplus metal lying at the sides of that which it is desired to retain. This results in elongating the wire, and consequently in a saving of metal, this 40 saving in the case of the ordinary wires amounting to from twenty-five to fifty per cent. of the total length.

45 By preserving the skin in the way described the nail, although flat on two sides, retains the strength of the original wire; but reducing the shank metal in one dimension necessarily decreases the base of union for the head and weakens the joint between it and the shank, the head being formed by crowding

or upsetting a portion of the metal at the end 50 of the shank. To overcome this tendency to weaken the nail at that point, I form it with expanding or flaring shoulders, which lie under the head along the flat or wider sides of the shank and strongly bind the two parts 55 together. Therefore the nail is as strong and tenacious as are those of the earlier form, which are round in section and which have a diameter equal to the larger diameter of mine, notwithstanding the fact above described that I 60 dispense with a large part of the metal of the round nail.

Under some circumstances it is desirable to force the nail into the wood in a certain direction in order to prevent too great a 65 strain upon it in the direction of the shorter diameter, and to assist in this I form a chisel-edge at the point, there being two tapering faces extending from the flat side to said edge, which latter is parallel to the longer diameter 70 of the shank. This cutting-edge enables me to so insert the nail that the flat sides shall lie in any desired direction; but, as concerns the shank portion and the head, some of the features of the invention can be preserved even though points of other forms be 75 employed. Again, to insure that the nail after being driven into place shall not turn axially under the strain of the fibers of the wood, and in order to prevent it from being 80 withdrawn longitudinally, I form a series of nicks or notches along the sides of the shank near the point or chisel-edge before referred to.

Figure 1 is a perspective view of a nail of 85 one form embodying my improvements. Fig. 2 is a view of the shank in section. Fig. 3 is a longitudinal section of the nail.

My improved nail or spike has a flat shank or body A, the flat sides or faces being indicated by a a and the edges by a' a'. The sides or faces a a are substantially parallel to each other both longitudinally and transversely of the shank. The edges a' a' are curvilinear in section, their outlines in section being substantially the arcs of a circle, the circle being indicated by dotted lines in Fig. 4. These edges a' a' are also substan-

tially parallel to each other from one end of the shank to the other. It will be seen that a nail of this configuration can be easily and cheaply made of a tough tenacious material, such as round wire. It possesses the strength of a round nail, although containing much less metal. The flat sides $a\ a$ can be formed with tough and hardened surfaces, so that they can be practically as strong as if there were present a larger mass of iron or metal of a more nearly crystalline structure.

B indicates the head. This may be circular, oval, or angular. In either case it is necessary to strengthen the joint or place of union of the head with the shank because of the weakening there, resulting from the reduction of the shorter dimension. This I accomplish by providing shoulders F F', preferably rounded or concave and integral with the surface metal on the flat sides $a\ a$, and also with the adjacent metal of the head B. I prefer also to form shoulders F' at the edges, as shown.

In the upper or outer face of the head B there is a small cavity or depression at C to receive the end of set-punch, the latter being thereby prevented from slipping from the head when the latter is being driven below the surface of a wooden object.

30 The point is indicated by D. It is formed with two flat sides $d\ d$, converging in a cutting-edge d' . These flat faces $d\ d$ are on the sides of the nail, where lie, respectively, the flat sides $a\ a$ of the shank. The edges of the point are indicated by d^2 , they being substantially extensions of the rounded edges $a'\ a'$ of the shank. The point, when thus constructed, constitutes a flat cutting-wedge. It can be used to open a passage for the nail in such way that the latter can be inserted in whatever position circumstances may require, and assists in preventing the nail from turning axially under the pressure or strain of the wood fibers. To further assist in this, and 45 also to prevent the nail from moving longitudinally, I form a series of nicks or small notches E E in the rounded side edges a' .

I am aware of the fact that nails or spikes of various forms have been heretofore made 50 with notches, corrugations, or the like, and do not broadly claim such construction as my invention.

I am also aware of the fact that nails of various forms, including cut steel nails substantially square or round in cross-section, and my own earlier triangular nails, have had shoulders at the point of union of the heads with the shank; but I am not aware of the fact that prior to my invention any one has 60 ever produced a flat but strong shank of substantially uniform dimensions from end to end, which, by reason of its flatness, (that is, having its breadth considerably greater than its thickness,) can be made much cheaper 65 than a round, square, or triangular nail, and

then has made such a form of shank practicable by joining it to the head through the medium of flaring or swelling shoulders, herein shown and described.

I herein use the terms "flat" and "flattened," and mean to be understood thereby as referring to the nail above set forth—namely, that the shank is of greater breadth than thickness, and has its larger sides or faces substantially parallel to each other from end to end and from side to side.

The head of the nail projects laterally in the direction of the flat sides. In this respect there can be variations; but I prefer to have it project uniformly over the several sides and edges, as shown. This is in contradistinction to nails having heads consisting merely of expansions longitudinally of the shank, and which in some instances extend slightly beyond the narrow edges, but are not flattened transversely of the axis of the shank, so as to project laterally over or overhang either of the flat sides.

It will be understood that I follow the plan heretofore well known for forming heads on wire nails—namely, by staving up some of the metal at one end, the staving action resulting in bending or flattening fibers of the metal out laterally.

What I claim is—

1. A nail having a shank of greater breadth than thickness and uniform throughout in breadth and thickness, and having a head at one end and a point at the other end tapered from the shank to a cutting-edge, substantially as described.

2. A wire nail having a flattened laterally-projecting head, a flat shank uniform throughout in breadth and thickness and of greater breadth than thickness, and having a point tapering from the thickness of the shank to a cutting-edge, substantially as set forth.

3. A nail having a flattened head which projects laterally over all sides of the shank, a point, and an intermediate shank which is flat from end to end—that is to say, uniform in breadth and thickness throughout, as set forth.

4. A nail having a flattened laterally-projecting head, a wedge-shaped point, and an intermediate shank which is flat from end to end—that is to say, of greater breadth than thickness and uniform throughout in breadth and thickness, and having rounded or curved edges between the broader sides or faces, substantially as set forth.

5. A nail having a head, a shank which is flat and uniform throughout in breadth and thickness, and has round or curved edges between the wider faces, and a point having flat faces converging to a cutting-edge which is parallel to the said wider faces of the shank, substantially as set forth.

6. A wire nail having a head formed of laterally bent or staved fiber of the wire, a shank

of greater breadth than thickness and uniform throughout in both breadth and thickness, and a point, substantially as described.

7. A wire nail having a head of laterally bent or staved fibers of wire, a wedge-shaped point, and a shank of greater breadth than thickness and uniform throughout in breadth

and thickness and having curved or rounded edges provided with nicks or notches, substantially as set forth.

WILLIAM TAYLOR.
